UNITED STATES PATENT OFFICE

2,168,557

TOP BUNKER REFRIGERATOR CAR

Charles D. Bonsall, Pittsburgh, Pa., assignor, by
mesne assignments, to Standard Railway
Equipment Manufacturing Company, a corpo-
ration of Delaware

Application November 22, 1937, Serial No. 175,762

12 Claims (Cl. 62—16)

The invention relates to refrigerator cars for handling perishable commodities and more particularly to what is known as the top bunker type of refrigerator car wherein an ice container is positioned adjacent the roof of the car and provided with a drip pan therebelow and spaced therefrom to provide a substantially horizontally disposed flue which communicates with a vertical flue associated with the vertical wall of the car, whereby air in the horizontally disposed flue being cooled and densified by the ice in the refrigerant container is caused to descend through the vertical flue from whence it rises through the foraminous false floor and then through the lading, and being warmed thereby, reenters the horizontally disposed flue and repeats the cycle.

One of the objects of the invention is to form the ice container so that a part of the melted ice will pass through the bottom thereof to the drip pan and a part of the melted ice will be temporarily retained in the container so that the melted ice so temporarily retained will help cool the air circulating through the horizontally disposed flue.

Another object is to provide means in the lower parts of the container so as to allow the melted ice to gradually escape from the container into the horizontally disposed flue over the drip pan so as to help cool the air circulating in the flue.

Another object is to form the lower parts of the container so as to retard the service movements of the car from swishing melted ice over the bottom of the container.

Another object is to form the drip pan so that it will retain some of the melted ice on the drip pan to aid in cooling the circulating air.

Another object is to form the drip pan to retard the service movements of the car from slushing melted ice around over the drip pan.

Another object is to form the ice container so that the melted ice escaping therefrom will be distributed over a relatively large area of the drip pan, or in other words, to evenly distribute such melted ice over the drip pan, and a further object is to also form the drip pan so that it will evenly distribute the melted ice over the width of the vertical flue associated with the vertical wall.

Another object is to provide means to prevent the melted ice as it descends through the vertical flue from being accumulated at one side thereof by the service movements of the car.

Another object is to combine the advantages of the improved ice container, drip pan and ver-

tical flue so that a large amount of heat will be absorbed from the melted ice as it moves from the refrigerant container through the horizontally disposed flue and vertical flue. Studies have developed that a great deal of the melted ice is now discharged from refrigerator cars at a temperature around 34° which means that it still has a great deal of heat absorbing capacity, and as numerous lading are carried in a refrigerator car around 45° to 50° temperature, it is the object of this invention to transfer more heat in the circulating air to the melted ice before it is discharged from the car.

In the drawing:

Fig. 1 shows part of a cross section of a railway refrigerator car incorporating some of my inventions.

Fig. 2 is a section on line 2—2 of Fig. 1 showing a horizontal section of the wall of the car and the associated vertical flue.

Fig. 3 shows the refrigerant container of Fig. 1 in perspective.

Figs. 4 and 5 show partitions for providing the vertical flue adjacent the side wall.

Fig. 6 shows a modification of the container of Fig. 3.

Fig. 7 is a modification of the containers of Figs. 3 and 6.

In the form of the invention illustrated one or more refrigerant chambers or containers 2 are preferably positioned on each side of the center line 3 of the car adjacent the roof 4 of the car and also preferably adjacent the side or other vertical wall 5 of the car. Hatchways 6 are provided in the roof above the container 2 for loading it with ice or other refrigerant. The usual hatch plug 7 and hatchway lid are used. The partition 10 is held in spaced relation to the side wall 5 by a series of vertical pieces 12 to form vertical flues 13 associated with the side wall 5. The insulated horizontally disposed partition or drip pan 15 is positioned below the refrigerant container 2 and spaced therefrom to provide a substantially horizontally disposed flue 16, which flue, however, inclines downwardly 45 toward and communicates with the vertical flue 13. A partition or member 11 extends upwardly from the inner margin of the drip pan 15 and is spaced from the refrigerant container 2 to provide a short vertical flue 18. The vertically disposed members 17 on opposite sides of the center line 3 of the car are spaced apart to provide an air channel or passageway 21. A floor rack or foraminous false floor 23 rests upon the insulated floor 24 and is spaced therefrom to pro-

vide a horizontal flue 25 which communicates with the vertical flue 13.

In such a refrigerator car air in the horizontally disposed flue 16 being cooled and densified by a refrigerant in the refrigerant container 2 moves down the downwardly and outwardly inclined drip pan 15 into the vertical flue 13, thence into the space 25 below the lading and rising through the apertures 25 in the foraminous floor 23, passes through or between the lading and being warmed and rarefied by the lading, rises and passes upwardly through the passageway 21 and vertical flue 18 into the horizontally disposed flue 16 from whence the cycle is repeated.

In the construction shown in Figs. 1 and 3 the bottom of the container is made of a metallic plate 30 formed with a plurality of substantially parallel corrugations 31 extending parallel to the wall 5 of the car so that the melted ice instead of running to the lower part of the inclined container is partially retained in the grooves 32 between the corrugations. The upper parts 33 of the corrugations are provided with apertures 34 (see Fig. 3) so that the overflow of melted ice may fall through to the drip pan 15. These apertures 34 are preferably dispersed over a large area at the bottom of the container 2 to sprinkle the melted ice over a large area of the drip pan 15. It may be desirable to provide relatively small apertures in the lower parts of the corrugations 31; that is, the valleys between the corrugations 31 to allow the melted ice to gradually escape from the container to the drip pan. These holes may also function as drain holes after the load has been removed from the car. The melted ice falling from the container to the drip pan passes through the horizontally disposed flue 16 and further cools the air passing therethrough.

In a railway car when the refrigerant containers 2 are positioned adjacent the side walls 5 thereof it is desirable to have as few hatchways 6 in the roof 4 of the car as possible owing to leakage of water and heat, therefore, refrigerant containers are made relatively long and extend lengthwise of the car so that normally it becomes difficult to load the container with ice in the portions of the container remote from the hatchway, particularly when the container has a mesh or open bottom, as the ice catches on the openings therein. However, in my construction the corrugations are preferably positioned parallel to the side wall of the car (as shown in Fig. 1) where they serve as runners so that ice may be easily slid to the remote portions of the containers. The walls of the container are preferably perforated.

In the construction shown in Fig. 6 the corrugations 38 extend normally to the wall 5 of the car and function to retard the service movements of the car from slushing the melted ice over the floor or bottom of the container. The corrugations may merge into a wall 39 of the container, as shown in Fig. 3, or terminate in the bottom of the container, as shown in Fig. 6.

In the specification I have used the word "corrugations" in the broad sense, meaning a plate formed with portions in spaced apart parallel planes connected by webs which function in the usual manner attributed to corrugations. Corrugating a metallic plate increases the heat exchange area between the refrigerant container 2 and a horizontally disposed flue 16 therebelow; furthermore, provides great stiffness and strength for the plate against deflection due to the weight

and impact forces of the refrigerant in the container. These corrugations are beams between opposite side walls of the container. However, ribs, baffles, or similar projections, shown as 40 in Fig. 7, may be used instead of corrugations 5 and still perform the desired functions.

I also preferably provide a drip pan 15 having the upper surface thereof made of a metallic plate 42 formed with a plurality of corrugations 43 which may extend parallel to the side wall of the car (as shown in Fig. 6) or normally thereto (as shown in Fig. 3) for the purposes and advantages set forth for the corrugations in the bottom of the refrigerant container. One of the objects of extending the corrugations in the 15 drip pan normal to the wall of the car (as shown in Fig. 3) is to provide means to distribute the melted ice evenly, or substantially so, over the width of the vertical flue. The drip pan is preferably insulated by, for instance, the boards 45. 20

One of the objects of the invention is to distribute the melted ice from the drip pan 15 evenly over the width of the vertical flue 13 associated with the side wall 5 but even when this is done service movements of the car may cause 25 the water to accumulate in one vertical side of the flue, therefore, I provide means to maintain the melted ice evenly distributed over the width of the vertical flue 13 as it passes therethrough. Such means may comprise a metallic plate 97 30 formed with a plurality of vertical corrugations 98 (see Figs. 1 and 2) which are preferably in alignment with corrugations 43 in the drip pan 15 when the corrugations 43 extend normally to the side wall of the car. Another means to accomplish 35 this purpose comprises a plurality of vertical partitions 12 which preferably are provided with spaced apart horizontal apertures 100 (see Fig. 5) so that air may pass between adjacent flues 13—13, while only a limited amount of water 40 will be allowed to pass through the partition. Fig. 4 shows a partition 12 provided with a plurality of notches 101 in each side thereof.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a roof having a hatchway therein, a wall having a vertical flue associated therewith, an ice container positioned below the hatchway, and a drip pan positioned below and spaced apart from the container to provide a horizontally disposed flue sloping toward and communicating with said vertical flue whereby air in the horizontally disposed flue being cooled and densified by a refrigerant in the refrigerant container is caused to descend through the vertical flue, the bottom of said container being formed so that part of the melted ice will pass therethrough to the drip pan and part of the melted ice will be retained in the container.

2. In a refrigerator car having a roof having a hatchway therein, a wall having a vertical flue associated therewith, an ice container positioned below the hatchway, and a drip pan positioned below and spaced apart from the container to provide a horizontally disposed flue sloping toward and communicating with said vertical flue whereby air in the horizontally disposed flue being cooled and densified by a refrigerant in the re-

5 frigerant container is caused to descend through the vertical flue, the bottom of said container being formed so that part of the melted ice will pass therethrough to the drip pan and part of the melted ice will be temporarily retained in the container.

10 3. A structure as defined in claim 1 wherein the bottom of the container is made of a metallic plate formed with a plurality of corrugations extending parallel to said wall and having apertures in the upper portion thereof.

15 4. A structure as defined in claim 2 wherein the bottom of the container is made of a metallic plate formed with a plurality of corrugations extending parallel to said wall with relatively small apertures in the lower part of the corrugations to allow the melted ice to gradually escape from the container.

20 5. A structure as defined in claim 1 wherein the bottom of the container is made of a perforated metallic plate formed with a plurality of corrugations.

25 6. A structure as defined in claim 1 wherein the bottom of the container is made of a metallic plate formed with a plurality of corrugations extending normally to said wall to retard the movement of the car from swishing the melted ice over the floor of the container.

30 7. A structure as defined in claim 1 wherein the bottom of the container is downwardly inclined toward the vertical flue and made of a metallic plate formed with a plurality of corrugations extending parallel to said wall and having apertures in the upper portion thereof.

35 8. A structure as defined in claim 1 wherein the bottom of the container is made of a metallic

plate formed with a plurality of corrugations and having apertures in the upper portion thereof, said apertures being dispersed over a large area of said bottom to sprinkle melted ice over a large area of the drip pan.

5

9. A structure as defined in claim 1 wherein the bottom of the container is made of a metallic plate formed with a plurality of corrugations and having apertures in the upper portion thereof, said apertures being dispersed over a large area of said bottom to sprinkle melted ice over a large area of the drip pan and the drip pan is made of a metallic plate formed with a plurality of corrugations extending normally to said wall to cause the melted ice to remain more evenly distributed over the drip pan.

10

10 10. A structure as defined in claim 1 wherein the drip pan is made of a metallic plate formed with a plurality of corrugations extending parallel to said wall to retain some melted ice in the drip pan.

15

11. A structure as defined in claim 1 wherein the drip pan is made of a metallic plate formed with a plurality of corrugations extending normally to said wall to cause the melted ice to remain more evenly distributed over the drip pan.

20

12. A structure as defined in claim 1 wherein the drip pan is made of a metallic plate formed with a plurality of corrugations extending normally to said wall to cause the melted ice to remain more evenly distributed over the drip pan, said corrugations extending to said vertical flue to cause said melted ice to be more evenly distributed over the vertical flue.
